FOREIGN PATENT DOCUMENTS

DE 3047532 A1 12/1980

Primary Examiner — Jonathan Liu*Assistant Examiner* — Patrick Hawn(74) *Attorney, Agent, or Firm* — Sherrill Law Offices, PLLC(57) **ABSTRACT**

A shelf upright extension kit with an elongated bottom extension rail with a transversely extending keyway and first and second extension panels. The extension panels each define a plane having first and second major surfaces, a pair of opposed ends and a pair of opposed edges. Each extension panel is fitted with a key configured and arranged for cooperatively engaging the keyway in the extension rail. The key extends within the plane of the extension panel proximate and parallel with a same edge. Included in the extension panel is a notch in a corner opposed to the key within the plane of the extension panel to allow the top end to fit flush with a bottom end of a side panel and the rear edge of the extension panel to fit flush with a wall.

UPRIGHT EXTENDER SYSTEM

BACKGROUND

10 Closet shelving systems have been manufactured and installed in residential and commercial buildings for storage of personal or commercial items. The size, strength and versatility of the closet shelving systems are of particular concern with any new or existing installation. The closed shelving system should be aesthetically pleasing while maintaining the desired functionality desired by the user. With storage space at a premium efficient use of shelving space is a must along with the ability to quickly and easily change the configuration or layout of the shelves with minimum need for tear down and reconstruction of the entire system.

15 In the prior art, closet shelves are constructed from plastic coated wire or partitioned wood sections and the size, strength and flexibility of the shelf is determined from that particular structure. However, such designs are limited by their construction size and weight bearing load and are difficult to change the layout once originally constructed.

U.S. Pat. No. 4,688,687 to Pryor describes a closet storage arrangement with vertical supports resting on the floor and a hang bar interposed between.

20 U.S. Pat. No. 5,322,173 to Kay describes a ventilated wooden shelf with cylindrical stubs attaching each separate flat shelf member to holes cut into support beams.

25 U.S. Pat. No. 2005/0184630 A1 to Bonanno et al. describes a storage system configured with support brackets which fit into pre cut cavities of opposing walls.

U.S. Pat. No. 2008/0224579 A1 to Juten describes a modular storage system with rails secured to a wall and the storage units that hang over the rails flush against the wall.

30 U.S. Pat. No. 6,988,628 to Krieger et al. describes a closet storage system with an engagable and lockable closet rod.

35 U.S. Pat. No. 7,255,237 to Stitchick et al. describes an organizer system with a mounting rail secured to a wall and support uprights which hang from the mounting rail secured by clips.

40 Closet shelves in the prior art are supported by wedges or notches on the side of the vertical support columns. A wall support, screwed or drilled to a wall has an extension piece extending off at an angle suitable to fit into the notch of the vertical column so as to "hang" the column off to one side of the wall support. The prior art wall support extension piece would fit into a cutout notch on the vertical column. The weight that can be supported by the shelf is dependent on the extension piece of the vertical column which fits into the notch on the column. At the angle which the extension piece protrudes to one side from the wall support subjects it to bend or break with increased load. In addition, the notch or cutout in the vertical column has a tendency to chip or crack lessening the supportable load and destroying the aesthetic appeal of the shelf system. Therefore, a need exists for a versatile, heavy weight supporting shelf system.

SUMMARY OF THE INVENTION

45 The first embodiment of the present invention is a shelf upright extension kit. The shelf upright extension kit includes an elongated bottom extension rail with a transversely extending keyway and first and second extension panels. The extension panels each define a plane having first and second major surfaces, a pair of opposed ends and a pair of opposed edges. Each extension panel is fitted with a key configured and arranged for cooperatively engaging the keyway in the

extension rail. The key extends within the plane of the extension panel proximate and parallel with a same edge. Included in the extension panel is a notch in a corner opposed to the key within the plane of the extension panel to allow the top end to fit flush with a bottom end of a side panel and the rear edge of the extension panel to fit flush with a wall. Furthermore, a set of alignment holes in the top end are spaced approximately equal distance from the front and rear edges. The alignment holes are configured and arranged to corporately engage an alignment pin. A set of support holes in the first surface are spaced approximately equal distance from the front and rear edges of the panel extension and are configured and arranged to corporately engage a C-Clip. A set of C-Clips and a set of alignment pins are included.

50 The second embodiment of the present invention method of installing a shelf upright extension kit. First step is obtaining a shelf upright extension system of the first embodiment. The alignment holes are fitted with the laterally extending alignment pins and aligned with the corresponding holes in a wall mounted side panel. The top end of the extender panel is mounted flush with the bottom end of the side panel and the rear edge is flush with the support wall. The extender panel is held flush against the side panel by mounting the c-clips fitted within the support holes.

BRIEF DESCRIPTION OF THE DRAWINGS

FIG. 1 is a side perspective view of the twin beam shelf with laterally extending lips.

FIG. 2 is a side perspective view of the twin beam shelf without the laterally extending lips.

FIG. 3 is an exploded side perspective view of the twin beam shelf with laterally extending lips.

FIG. 4 is front perspective view of a key.

FIG. 5 is a side view of a key.

FIG. 6 is a side view of top and bottom keys mounted to the top and bottom surfaces of the side panel.

FIG. 7 is a side view of top and bottom rails.

FIG. 8 is a front perspective view of the wall shelf support assembly with the rails, keys and side panel.

FIG. 9 is the wall shelf support assembly of FIG. 8 with a twin beam shelf mounted therein.

FIG. 10 is a side view of a C-Clip.

FIG. 11 is a front view of the C-Clip fastened to the side panel and extension panel.

FIG. 12 is a side view of the C-Clip fastened to the side panel and extension panel depicted in FIG. 11.

FIG. 13 is an exploded side perspective view of the extension panel assembly mounted to the wall shelf support assembly.

FIG. 14 is a side perspective view of the extension panel assembly mounted to the wall shelf support assembly.

- Construction

Depicted in FIGS. 4-9 and 12, the wall shelf support kit is assembled on a support wall 200 with a plurality of twin beam shelves 10 that may be secured to the opposing side panels 70. The wall shelf support kit includes top and bottom rails 52, 51, two opposing side panels 70 and first 61 and second 62 keys secured to the top 72 and bottom 71 ends of the side panels 70. The first and second keys 61, 62 are mounted to the side panel 70 and secure the side panel 70 to the wall 200.

Referring to FIGS. 1-3, the twin beam shelf 10 has a dual wood or hybrid wood construction. Both the support structure 20 and the front and rear beams 32, 30 are a wood grain material including, but not limited to particle board, plywood or hardwood. The hardwood would include maple, oak, poplar, cherry, ash, walnut, hickory, mahogany, alder, aspen, basswood or beech. The twin beam shelf 10 consists entirely of wood grain materials which is preferable for cutting and fitting during installation. In addition, the dual wood construction is available for a finished wood appearance. The support structure 20 and beams 30, 32 may be stained to a desired color allowing for unique shelving designs. When the support structure 20 of the twin beam shelf 10 is plywood or particle board a wood grain melamine laminate print may be used to represent a stained hardwood finish. The front and rear beams 32, 30 which may be a hardwood when the support

structure 20 is plywood or particle board, may have a commercially available ultra violet waterborne finish to match the coloring of the support structure 20.

Referring to FIG. 3, the twin beam shelf 10 includes front and rear rabbet cut edges 25, 23 of the support structure 20 spaced in the longitudinal direction x. Front and rear beams 32, 30 have front and rear dados 36, 38 defined as a rectangular grooves cut into the beams 32, 30 respectfully. The front and rear rabbet cut edges 25, 23 cooperatively engage the front and rear dados 36, 38 forming a four sided adhesive joint 26. An adhesive, such as wood glue, covers the four flush surfaces of the adhesive joint 26 securing the front and rear beams 32, 30 to the support structure 20. The four sided adhesive joint 26 extends the length of the support structure 20 greatly increasing the strength and shelf weight. A twin beam shelf 10 may extend approximately 60 inches in length, as opposed to the industry standard 30 inches, without intermittent bracing or underneath supports and without losing significant support strength. Because the twin beam shelf 10 is made of all wood grain material the size may be cut to fit any desired space greatly increasing the room for storage.

FIG. 1 depicts the front and rear beams 32, 30 extending in the lateral direction y below the second major surface 24 of the support structure 20 forming front and rear lips 34, 33. One example of the dimensions of the twin beam shelf 10 depicted in the FIG. 1 include a length of up to 60 inches, a shelf width in the longitudinal direction x of approximately 6-16 inches and an approximate 0.5-1 inch front and rear lip 34, 33 laterally extending from the second major surface 24 of the support surface 20. Longer shelving lengths ranging up to 60 inches are available and are proportional to the increased thickness and width of the support surface 20. The approximate measurements of the particular characteristics of the twin beam shelf 10 are dependent on the accuracy of the wood cuts and the saws used to make such cuts. These measurements are approximate and may be modified to fit a particular application or design.

A second embodiment in FIG. 2 depicts the support structure 20 with the front and rear wooden beams 32, 30 that do not extend laterally below the second major surface 24 but are flush with the first and second major surfaces 22, 24 of the support structure 20. The edges 25, 23 of the support structure 20 have a multiple side adhesive joint 26 cooperatively engaging the beams 32, 30. This shelf 10 without the lateral lips of the first embodiment still offers the increased support strength compared to the industry standard shelves and allows the edge to edge length to extend at least 60 inches with minimal loss of strength.

The wall shelf support kit shown assembled in FIGS. 8-9, includes a set of rails 50 that are secured to a wall 200 and extend along the wall in a transverse direction z. A set of opposing side panels 70 define first and second major surfaces 77, 79 and front and rear edges 73, 75. First and second keys 61, 62 are fitted to the keyway 56 of the lower and upper rails 51, 52 respectfully and securing it to the wall 200. A lower rail 51 is secured at a user determined distance off the ground and will act as a support anchor for the side panel 70 such that the side panel 70 that will rest on the lower rail 51. The top rail 52 is spaced an approximate vertical distance from the lower rail 51 and secured to the wall 200. The top rail 52 serves as a top support and guide rail for the side panel 70. A spacer (not shown) may be used to allow the user to correctly space the upper and lower rail 52, 51 without the use of a separate measurement instrument. The upper and lower rails 52, 51 extend flush against the length of the wall 200 for the desired length of the twin beam shelf 10. The user is allowed to adjust the length of the twin beam shelf 10 to fit their particular

design preferences and the length of the shelf **10** may extend up to 60 inches. A keyway **56** continuously extends the length of the rails **51, 52** allowing the first and second keys **61, 62** to attach within the keyway **56** anywhere along the rails **51, 52** thus easily adjusting the length of the twin beam shelf **10**. An object (not shown) may insert within the keyway **56** to act as a stopper preventing the first and second keys **61, 62** from sliding out of position. The inserted object (not shown) may include but not limited to a screw or nail wedged in the keyway **56**.

In FIG. 6, a first key **61** is mounted to the bottom end **71** of the side panel **70** and a second key **62** is mounted to the top end **72** either by nailing, screwing or fastening to pre-existing C-clip mounting holes **74** in the side panel **70**. The opposing side panels **70** range from 24-48 inches in vertical height. The first and second keys **61, 62** have extending pegs **66** which fit securely into top and bottom ends **72, 71** of the side panels **70** with an adhesive applied to secure the pegs **66**. The first and second keys **61, 62** comprising the set of keys **60** may also be nailed or screwed in. The side panels **70**, additionally, have predrilled alignment holes **76** in the top and bottom ends **72, 71** that will align with the alignment holes **122** drilled in a panel extension **110** ensuring a straight extension of the shelving uprights if a shelving height greater than 48 inches is desired.

As shown in FIGS. 4-6, an arm **64** extends laterally from the base of each first and second keys **61, 62** in the same plane as the side panels **70**. The arm **64** is at a close proximate distance to the rear edge **75** of the side panel **70** and extends laterally parallel with the rear edge **75** and is configured and arranged to frictionally secure within the keyway **56** within the upper and lower rails **52, 51** respectfully. The extending arm **64** has a rounded arm surface **65** to allow for easier slippage into the keyway **56**. The first and second keys **61, 62** referred to as a set of keys **60**, each include a fastener **68** that may be pounded in with a hammer to the side of the side panel **70**. The fastener **68** prevents the first and second keys **61, 62** from twisting and shifting when mounted on the side panel **70**. By preventing shifting the overall shelf construction is more stable. When the set of keys **60** are frictionally secured in the set of rails **50** movement is restricted and side panel **70** stabilized. The frictionally secure set of keys **60** within the set of rails **50** secures the side panel **70** to the wall **200**.

FIG. 7 depicts a side view of the set of rails **50** that are a wood grain and screwed, nailed or secured using an adhesive to the support wall **200**. The upper and lower rails **52, 51** would extend along the wall **200**. A recess **53** may be present on the forward facing side of the upper and lower rails **52, 51** to obscure a nail or screw extending through to the support wall **200**. The upper and lower rails **52, 51** have a keyway **56** to receive and secure the set of keys **60**. The rounded edges **58** of the keyway **56** allow the arm **64** of the first and second keys **61, 62** to easily snap into place and be friction secured within the keyway **56**. There is no need for additional tools or adhesives to secure the set of keys **60** to the set of rails **50**.

As depicted in FIGS. 8-9 set of rails **50** secure the side panel **70** so the side panel **70** does not hang off the set of rails **50** where torque on the rails may cause damage to the wall **200** or chip or crack the side panel. The bottom rail **51** is mounted so that the side panel **70** will rest on it with the top wall anchor **52** securing the top end **72**. Because the side panel **70** does not hang off of a protruding extension piece, the support weight of the side panel **70** is not dependent on an extending piece eliminating the danger of the protruding extension bending or snapping. No notches or grooves are cut into the sides of the side panel **70** and the protruding extension piece will not need to be fit into a notch carved out of the side

panel **70**. Eliminating wedges or cuts into the side panel **70** eliminates the possibility that chips or cracks may develop within or around the wedge due to prolonged use or exceeded weight limitations.

The side panels **70** range from 24-48 inches. The side panels **70** may be extended to a height of up to 72 inches using the panel extension **110**. The increased vertical height is achieved by extending the length of the opposing side panels **70**. A panel extension **110** may be mounted to either the top end **72** or bottom end **71** of the side panel **70** extending the overall vertical distance of the system. The panel extension **110** may mount to either top or bottom ends **72, 71** of the side panels **70** depicted in FIGS. 13 and 14.

Depicted in FIGS. 13-14, the upright extension or panel extension kit includes a panel extension **110**, metal alignment pegs **120** and a set of C-Clips **130**. The panel extension **110** has a notch **112** cut into a corner that corresponds to the position of either the top or bottom rails **52, 51** mounted to the support wall **200** allowing the panel extension **110** to fit flush with the support wall **200** and side panel **70**. The notch **112** is located on the opposing corner of the mounted key **60**.

FIGS. 12-14 show the side panel **70** mounting between two rails **51, 52** bracing the side panel **70** to the wall **200**. The side panel **70**, the first and second keys **61, 62** and they are in the same plane defined by the side panel **70** when secured to the top and bottom rails **52, 51**. The panel extension **110** defines first and second major surfaces **114, 116** and top and bottom **118, 119** and front and rear edges **113, 115** along with a notch **112** to fit around a mounted individual in a set of rails **50**. The notch **112** cut into the corner defined by the intersection of the top end **118** and the rear edge **115** allows the panel extension **110** to fit around the bottom rail **51** and flush with the side panel **70** and the wall **200**.

The panel extension **110** is up to 24 inches long and has a notch **112** cut out on at least one end to allow the panel extension **110** to fit around the bottom or top rails **51, 52** while still aligning with the mounted side panel **70** flush against the wall **200**. The alignment holes **76** in the side panel **70** match with the alignment holes **122** in the panel extension **110** and are lined up with an alignment pin **78**. The alignment holes **76** in both the side panel **70** and panel extension **110** align all sides so a smooth, seamless transition occurs between the side panel **70** and the panel extension **110** keeping with the overall aesthetic quality of the shelving arrangement. The notch **112** is in the opposing corner of the panel extension **110** as the mounted key **60**.

The panel extension kit in FIGS. 13-14 wherein the panel extension **110** is secured to the side panel **70** by the C-Clips **130**. A third bottom extension rail **140** is attached to the wall **200** below the panel extension **110** for support similar to the bottom rail **51** supporting the opposing side panels **70**. The bottom end **119** has a key **60** attached and frictionally secured within the bottom extension rail **140**. The arm **64** is in the same plane as the extension panel **110** and the side panel **70**. The side panel **70**, set of three keys **60**, and the extension panel **110** are all in the same plane defined by the side panel **70** and panel extension **110** and proximate and parallel with the rear edge **75** of the side panel **70** and rear edge **115** of the panel extension **110** when mounted to the set of three rails **50**. A second embodiment is to mount the panel extension **110** on the top side of the side panel **70** extending the closet assembly in the upward vertical direction.

FIGS. 10-14 show a C-Clip **130** which fits into either the inner or outer sides of the side panel **70** or panel extension **110**. The C-clip **130** may securely mount in the holes **74** which may be drilled in the panel extension **110** and side panel **70**. The C-Clip mounting holes **74** are spaced approxi-

mately equidistance from the front and rear edges 113, 115 of the panel extension 110 on a first major surface 114 to offer greater support when connected to the side panel 70. The C-Clips 130 may also be secured to the side panel 70 by drilling a hole in any user desired location. When the panel extension 110 is secured to the side panel 70 a plurality of twin beam selves 10 may be installed wherein the user determines the number of shelves, drawers and hang space as well and vertical and horizontal size of the twin beam shelf 10.

I claim:

1. A shelf panel extension kit, comprising:
  - a) an elongated bottom extension rail with a transversely extending U channel keyway having a laterally extending opening along the entire transversely elongated rail,
  - b) first and second extension panels each defining a laterally extending plane and having,
    - i) first and second major surfaces, a pair of laterally opposed top and bottom ends and longitudinally opposed front and rear edges,
    - ii) a key fitted into one of the laterally opposed ends of the first and second extension panels and configured and arranged for cooperatively engaging the keyway in the extension rail wherein the key extends within the laterally extending plane of the extension panel proximate to and parallel with one of the longitudinal edges,
    - iii) a notch in a corner laterally opposed to the key within the laterally extending plane of the extension panel and configured and arranged to allow the laterally opposed end to fit flush with a side panel of a shelf support kit and one of the longitudinal edges of the extension panel to fit flush with a wall,
    - iv) a set of alignment holes in at least one end spaced approximately equal distance from the front and rear edges, the alignment holes are configured and arranged to corporately engage an alignment pin,
    - v) a set of support holes in the first surface spaced approximately equal distance from the front and rear edges of the extension panel and configured and arranged to cooperatively engage a C-Clip,
  - c) a set of C-Clips, and
  - d) a set of alignment pins.

2. The shelf panel extension kit in claim 1 wherein the adjoining inlays are a metal alloy.

3. The shelf panel extension kit in claim 1 wherein the extension rail and first and second extension side panels are made from a material selected from a group which includes hardwood, plywood, and particle board.

4. The shelf panel extension kit in claim 1 further including a twin beam shelf.

5. The shelf panel extension kit in claim 4 wherein the length of the shelf is greater than 30 inches.

6. A method of installing a shelf panel extension kit comprising the steps of:

- a) identifying a primary shelf support assembly mounted upon a vertical surface, the mounted primary shelf support assembly having at least (1) a horizontally extending base rail rigidly attached to a vertical surface, and (2) first and second planar primary side panels vertically supported upon the base rail, each having (i) an inward facing major surface and an outward facing major surface (ii) a top end and a bottom end, (iii) a front edge and a back edge, and (iv) vertically extending open grooves in the outward facing major surface at the bottom end of the primary side panel,
- b) obtaining a shelf panel extension kit according to claim 1,
- c) securing the extension rail to the vertical surface a distance below and in parallel alignment with the base rail,
- d) abutting the top end of each extension side panel with the bottom end of a primary side panel and vertically aligning the laterally extending open grooves in the extension side panel with the vertically extending open grooves in the primary side panel to form a set of matched grooves,
- e) inserting an adjoining inlay within each of the matched grooves with the inlay in physical contact with both the primary side panel and the extension side panel to form a joined side panel set, and
- f) engaging the key on the extension panel within the keyway in the bottom extension rail.

7. The method of claim 6 further comprising the step of supporting a shelf between and with the first and second installed extension side panels.
